[57] CLAIM

The ornamental design for a watch casing and bezel, as shown and described.

DESCRIPTION

FIG. 1 is a perspective view of a watch casing and bezel showing our new design;

FIG. 2 is a left side elevational view thereof;

FIG. 3 is a top plan view thereof;

FIG. 4 is a right side elevational view thereof;

FIG. 5 is a first end elevational view thereof;

FIG. 6 is a second end elevational view thereof;

FIG. 7 is a bottom plan view; and,

FIG. 8 is a perspective view in accordance with a second embodiment of our invention.

The left side elevational, top plan, right side elevational, first end elevational, second end elevational and bottom plan views are similar to those respective views illustrated in FIGS. 2-7, except when in this alternate embodiment the five (5) notched areas on the bezel have been deleted and the crown has been depicted in broken lines.

The broken-line showings are environmental only and form no part of the claimed design.
